H. KERSHAW,

INTERNAL GRINDER OR MILL FOR USE IN LATHES, BORING, DRILLING, AND OTHER MACHINE TOOLS.
APPLICATION FILED MAR. 2, 1918.

1,298,963.

Patented Apr. 1, 1919.

THE NORRIS PETERS CO., PHOTO-LITHO., WASHINGTON, D. C.

UNITED STATES PATENT OFFICE.

HARRY KERSHAW, OF MANCHESTER, ENGLAND.

INTERNAL GRINDER OR MILL FOR USE IN LATHES, BORING, DRILLING, AND OTHER MACHINE TOOLS.

1,298,963.

Specification of Letters Patent.

Patented Apr. 1, 1919.

Application filed March 2, 1918. Serial No. 220,037.

To all whom it may concern:

Be it known that I, HARRY KERSHAW, a subject of the King of Great Britain and Ireland, and a resident of Manchester, 5 county of Lancashire, England, have invented a certain new and useful Improvement in Internal Grinders or Mills for Use in Lathes, Boring, Drilling, and other Machine Tools, of which the following is a 10 specification.

This invention relates to internal grinding, milling, cutting and like machines of the type in which the grinding wheel or cutter is carried upon a rotary spindle which is 15 eccentrically or radially adjustable for the purpose of feeding the grinding wheel or cutter to the internal surface of a cylinder or other work to be machined, and to the type in which the grinder, or mill or attachment 20 comprises a fast-moving member and a slow-moving member consisting of two parts secured together in eccentric relation to one another but moving as one, means for varying the eccentricity of the slow-moving 25 member and means for driving said fast and slow-moving members independently of one another.

The present invention consists in certain 30 novel combinations and arrangement of parts as hereinafter described and pointed out in the appended claims.

The invention although hereinafter described and illustrated as applied to the nose of both hollow and solid lathe mandrels, 35 is equally applicable for use with drilling, milling and other machine tools having hollow mandrels without any changes other than a change in the speed of rotation and the substitution of a cutter.

40 Of the accompanying sheets of drawings:

Figure 1 is a longitudinal sectional view of the grinder or mill mounted on the nose of the hollow mandrel of a lathe and set up 45 to the work.

Fig. 2 is a section taken on line α , α of Fig. 1.

Fig. 3 is a front view of the rear member of the two-part slow-moving member.

50 Fig. 4 is a section taken on line y , y of Fig. 2.

Fig. 5 is a sectional view showing the means employed for driving the fast-moving

member when the invention is applied to a machine tool having a solid mandrel. 55

Fig. 6 is a section taken on line z , z of Fig. 5.

Like letters of reference indicate corresponding parts in the several figures.

Referring to the drawings,— a is the hollow mandrel and b its nose which carries the slow-moving member which is constituted by a back and chuck-like member c screwed on to said nose, and a flanged and tapered sleeve or front member d . These 65 back and front members c and d are secured together in eccentric relation to one another by means of two studs e and f , which studs e and f are carried by the flange of the sleeved and front member d and extend through the 70 flange of the back member c . Of these studs, the stud e is a master stud and serves as a pivot by which the front member d can swing, while the other stud f passes through a radial slot g —Figs. 2, 3 and 4—in the 75 flange of the rear member c , said studs e and f being provided with nuts h which lock the two members together in place after having been set over on a cut.

i is the grinding wheel carried by the 80 fast-moving member which is constituted by a flexible shaft and pulley j —Fig. 1—driven from a countershaft (not shown) and at grinding speed, said flexible shaft consisting of three parts or spindles k , k' , k'' coupled together by means of universal joints k^3 , which joints k^3 , when the sleeved member d is thrown off centers up to its work, allowing of the floating spindle k' taking up 85 an angle corresponding to the distance between the two centers of rotation, and the spindle k to be pulled slightly forward, the rear end k^4 of said spindle k being made square to slide in the pulley j by which it is 90 driven, while the front end k^5 of said spindle k takes in suitable bearings c^* in the 95 chuck-like member c of the slow-moving member.

The nose end d' of the sleeved member d is provided with means for preventing dust 100 creeping into the bearings of the spindle k^2 , and such means may consist in slightly counter-sinking the face d^2 of said nose end d' and covering the same with a cap l which presses a series of soft asbestos or cotton 105 composite washers l' against said face d^2 .

with sufficient pressure to keep dust from creeping in and oil from creeping out, but not enough to retard the speed of the spindle k^2 or to overheat the same.

5 The fine adjustment, or cut, or set, viz:—the eccentricity of the sleeved member of the slow-moving member carrying the spindle k^2 of the fast-moving member or flexible shaft is effected by means of a fine pitched screw m —Figs. 3 and 4—fitted in and across the flange of the slow-moving member c and screwing through a block n slidably mounted in a recess o in said flange, said block n being provided with jaws n^* which embrace 10 the stud f carried by the flange of the sleeved and slow-moving member d . This screw m when turned by a key or the like shifts the block n along the recess o , and by 15 the engagement of its jaws n^* with the stud f which extends through the radial slot g causes the sleeved member d and fast-moving spindle k^2 to be thrown, the floating spindle k' moving accordingly, over on the stud f ever so little, or the full range as required, the jawed block n engaging said stud 20 f with clearance for the radial movement.

In the arrangement shown in Figs. 5 and 6, the fast-moving member is driven through toothed gear in the following manner:—On 25 the spindle k^2 of the fast-moving member is mounted a pinion k^4 located in the bore c' of the slow-moving member c , and this pinion k^4 meshes with a pinon c^2 rotatably mounted on a stud c^3 fixedly carried by the member c . 30 This pinion c^2 which extends through a slot in the wall of the boss of the member c engages with the internal teeth c^4 of a ring c^5 , said ring c^5 , which surrounds the boss of the slow-moving member c , being rotatably 35 mounted on ball bearings and provided with flanges to form a flanged pulley c^6 which is driven by a belt q from a countershaft (not shown).

In action, external wheel or ring c^5 drives 40 pinion c^2 at increased speed, pinion c^2 drives pinion k^4 and with it spindle k^2 , which spindle k^2 transmits rotation to grinding wheel i in the manner before set forth. The inner end of spindle k^2 is made square so that it 45 may slide in the pinion k^4 when the grinding wheel is set over to work as in the previous arrangement. Instead of the fast-moving spindles k and k^2 being coupled together by floating spindle k' and universal joints k^3 , 50 said spindles k and k^2 may be connected together by flexible cable shaft working without universal joints.

Having now described my invention, what I claim as new and desire to secure by Letters Patent of the United States is:—

1. An internal grinder or mill for use in solid mandrel lathes, boring, drilling and other machine tools, comprising a slow-moving member consisting of a back or nosed 60 member and a sleeved front member carry-

ing a spindle rotatably mounted therein, said back and front members being pivotally connected together so as to be set in eccentric relation to one another, means for varying the eccentricity of said back and front members, a grinding wheel or other cutter carried by said spindle, a bearing located in the bore of the back or nosed member, a spindle rotatably mounted in said bearing and in the hollow mandrel, flexible means connecting 75 said two spindles, said flexible means being located in the sleeved slow-moving member, a pinion fixed to the spindle mounted in the back or nose member, a pinion loosely mounted in and carried by the body of said 80 nose member and engaging the aforesaid pinion and an internally toothed ring or pulley engaging said second pinion, said toothed ring or pulley being mounted exteriorly of the boss of the back member and carried on 85 ball bearings.

2. A grinding attachment for lathes including the combination with the lathe spindle, of a flanged slow moving member detachably fitted to said spindle, an anti-friction bearing housed in said slow moving member, a substantially cone shaped hollow casing member pivotally connected to the flanged portion of the slow moving member at its large end, and means for shifting said 95 casing eccentrically on the face of said slow moving member, a flexible high speed shaft housed within said casing member and slow moving member, said shaft consisting of a cutter carrying section journaled in the small end of the cone shaped housing, a driven shaft section journaled in the anti-friction bearing of the slow moving member, and an intermediate coupling section having 100 a universal joint connection respectively 105 with the ends of the cutter carrying and driven sections of the shaft, said coupling section being located wholly within the enlarged tapered portion of the housing adjacent the slow moving member.

3. A grinding attachment for lathes including the combination with the spindle thereof, a slow moving member detachably fitted to said spindle and consisting of a flanged face portion and a hub portion having therein a threaded socket for receiving the threaded end of the lathe spindle, and an anti-friction bearing at one side of the threaded portion, a substantially cone shaped housing pivotally carried by the flanged portion of the slow moving member, means for shifting the entire housing eccentrically with reference to the slow moving member, a high speed shaft having the major portion thereof concealed within the cone shaped housing and consisting of a cutter carrying section journaled in the forward end of said housing, a driven section journaled in the anti-friction bearing of the slow moving member, an intermediate coupling 115 120 125 130

section having universal joint connections respectively with the cutter carrying and driven sections, and means for drivng said driven section consisting of a gear carried thereby adjacent the anti-friction bearing, a 5 stub shaft mounted in the slow moving member parallel to the driven section, a gear on the latter shaft meshing with the gear on the driven section of the high speed shaft, and a 10 driving pulley rotatably mounted on the

hub portion of the slow moving member and having an interior rack for meshing with the gear on the stub shaft.

In testimony whereof I have affixed my signature hereto this 24th day of January, 15 1918.

HARRY KERSHAW.
